Figure 1 is a side view of my newly-designed knife-handle, and Fig. 2 shows the reverse side thereof. Figs. 3 and 4 are sectional views of the handle, one being longitudinal and the other transverse.

The leading feature of my design consists in a knife-handle having one side ornamented with a representation of a full-length figure of a woman in full dress.

Another feature consists in a knife-handle one side whereof is ornamented with the representation, in face view, of the full-length figure of a woman in full dress, and the other side is ornamented with a representation of the woman's back, substantially as herein described and shown.

In the drawings, A represents one side of the handle, whereon is represented the front or face view of the woman. As there shown, she is represented in full dress, with a lace scarf ³⁰ c depending from the head. The side B, being the other side of the handle, shows the woman's back, the principal feature of this part of the design being the veil d and the dress-skirt e.
